UNITED STATES PATENT OFFICE.

GEORGE GRUNBERG, OF NEW YORK, N. Y.

DESIGN FOR A PERFUME CONTAINER.

Application filed December 14, 1923. Serial No. 8,032. Term of patent 3½ years.

To all whom it may concern:

Be it known that I, GEORGE GRUNBERG, a citizen of the United States, residing at New York city, county of New York, borough of Manhattan, and State of New York, have invented a new, original, and ornamental Design for a Perfume Container, of which the following is a specification, reference being had to the accompanying drawing, forming part thereof.

I claim:—

The ornamental design for a perfume container, as shown.

GEORGE GRUNBERG.
